UNITED STATES PATENT OFFICE.

EDWIN R. PHILLIPS, OF EL PASO, TEXAS.

FUEL-ECONOMIZER.

957,173.

Specification of Letters Patent.

Patented May 3, 1910.

Application filed October 19, 1908. Serial No. 458,457.

To all whom it may concern:

Be it known that I, EDWIN R. PHILLIPS, a citizen of the United States, residing at El Paso, in the county of El Paso and State of Texas, have invented new and useful Improvements in Fuel-Economizers, of which the following is a specification.

My invention relates to fuel economizers, and pertains especially to draft regulating appliances for use with locomotive and other boilers.

In firing under a boiler it has always been difficult to regulate the air supply necessary for combustion so as to get the right quantity of air at the right time to produce the best results. In the admission of air above the flames of a furnace immediately after firing, the trouble has been to control the air so that a known quantity might quickly reach the distilled gases for their combustion, and then be able gradually to cut off the air as the fire becomes incandescent toward the coke stage, so that as the fire reaches this stage the upper air will be cut off entirely, burning the coke through the grate alone. I have provided a simple, practical arrangement by which I am able to effect this control of the air, and my invention has other objects and advantages, as will be made manifest hereinafter.

The invention consists of the parts and the construction and combination of parts as hereinafter more fully described and claimed, having reference to the accompanying drawings, in which—

Figure 1 is a front view of boiler-head. Fig. 2 is a longitudinal vertical section of the fire-box and air heater. Fig. 3 is a vertical section on line 3—3 of Fig. 2. Fig. 4 is a detail view of cylinder and piston. Fig. 5 is a detail section on line 5—5 of Fig. 3.

While I have shown the invention as applied particularly to a locomotive boiler, it will be manifest that it is applicable under any type of boiler where an air control such as the present invention comprehends is applicable.

A represents the boiler of a locomotive, 2 the combustion chamber, and 3 a brick arch arranged in the combustion chamber and extending above the fire and also over the air-heating box 4.

The arrangement of the air-box 4, and the means for controlling the entry of air thereinto for the purposes of facilitating

combustion, constitute the main features of the present invention.

In the arrangement here shown, of the air-box as applied to the fire-box of a locomotive, the air-box is disposed at the front of the fire-box and air is admitted thereinto through one or more air-pipes 5. The walls of the air-box are made of fire-brick or other suitable material, and suitably reinforced or held in position by water-pipes or other appropriate means. The interior of the lower portion of the air-box which is in communication with the inlet pipes 5 is divided into flues 6 which open upward into a superheater and expansion chamber 7, which latter is partly arched over, as represented at 8, near the bottom of the doors 9, and the top of the superheater chamber 7 has a series of air outlets 10 discharging into the fire-box above the fuel. The area of the flues 6 is preferably greater than the area of the air outlets 10, and the size and disposition of the superheater chamber 7 are such that the air will measurably back up into the superheater or expansion chamber 7 before escaping into the fire-box. Also it is to be noted that the bricks forming the walls of the superheated air outlets 10 are arranged at a considerable incline and are protected more or less by the shelf 8, so that coal fed into the furnace will not fall through the air openings.

The overhanging arch 3 extends from above the door to a point just behind the bridge wall at the rear of the grates and operates to prevent the gases coming in contact with the boiler. This overhanging arch assists in retaining at a very high temperature the released gases from the fuel, and also superheats the air as it escapes into the fire-box from the air-box 4.

In order to effect perfect combustion of the carbon, it is essential that the chamber into which the gas escapes is surrounded by as many superheated walls as possible to prevent cooling of the hydrocarbon gas.

In order to render this system of air heating and air feed effective, some means must be provided by which the amount of air admitted to the fire-box and over the fuel after each charge of fresh coal, can be definitely regulated. It is therefor that I provide the following means: The doors 9 are here shown as ordinary sliding doors working in suitable guides 11 and operated by a well-known arrangement of levers 12—13. Each door

2
carries a roller 14 which, when the door is shoved back, strikes a stiff-leaf spring 15 carried on a rocker arm 16 which is fulcrumed at 17 on the furnace front or boiler head.

Inasmuch as the invention comprehends one or more swinging arms 16 and one or more air inlets 5 with corresponding dampers 18 and mediate connections between a 10 swinging arm and a corresponding damper, and as the parts for each door are substantially alike, I shall merely describe one swinging arm and its connections with its damper. The arm 16 is connected by a link 15 19 with the vertical slide 20 working in suitable guides 21. The slide 20 is connected by suitable means, as the rod or wire 22, with the damper 18 which controls an inlet to the air-box 4. With the arrangement here 20 shown, when a door 9 is opened its roller 14 strikes the spring 15 which yields enough to avoid shock and jar and causes the arm 16 to rock, lifting the slide 20 and opening the damper 18.

25 In order to effect a slow closing movement of the damper, I provide appropriate means, as follows: 23 is a fluid cylinder preferably containing oil, in which a piston 24 operates. The piston has a rod 25 extending out 30 through one head of the cylinder and connected by a bracket 26 with the slide 20. The piston 24 is provided with valves 27 which will open when the piston is lifted and allow the fluid to flow rapidly from the 35 space above the piston and through the piston to the space below. When the door 9 is closed, the weight of the moving parts will leave the piston free to fall again, but the return of the fluid from the lower end to 40 the upper end of the cylinder takes place through a restricted port or by-pass 28 in which is interposed a regulating valve 29. The speed with which the piston falls, and with which the air-valve or damper 18 closes, 45 is regulated by the valve 29. It is understood that the fluid cylinder 23 is merely a convenient form of check or brake to regulate the period of closing of the damper 18, and it is manifest that various equivalent 50 devices could be used to effect the same ends.

In operation, when it is desired to fire under the boiler, the doors 9 are opened. As the doors open, the roller 14 causes the arm 55 16 to rock and lift the slide 20 and open the damper or dampers 18. This lets in the air to the air-box 4 where it rapidly becomes heated by contact with the hot bricks. In the swinging upward of the arm 16 to open the damper, the slide 20 is carried upward, 60 and with it it carries the piston 24, which latter moves through the fluid in the cylinder by reason of the free opening of the valves 27. When the doors are closed, the air drafts through the box 4 and over the top of 65 the coal in the furnace continue until such

time as the piston 24 falls back to the bottom of the cylinder and closes the valve 18. The time that it takes the piston 24 to travel through the cylinder by gravity is regulated by the valve 29, and this is done in accordance with the time necessary to effect proper combustion of the distilled gases from the fresh coal and reduce the coal to a coke stage. At that time the damper is closed, the top feed of air into the furnace is discontinued 70 through the box 4, and thereafter the coke is burned by mixing with the air which comes through the grates alone.

With a given quantity of coal fed to the furnace each time, it is readily determined 80 what quantity of air should be admitted through the air-box and for how long a time after the doors are closed.

Having thus described my invention, what I claim and desire to secure by Letters Patent is—

1. The combination of a boiler and a fire-box, a door therefor, an air-heating box within the fire-box and adjacent to and below the door, a protecting shelf between the 90 door and the outlet end of the air-heating box, an arch in the fire-box arranged at an incline and extending from a point above and adjacent to the door downwardly toward the rear of the fire-box, said arch operating to prevent the gases coming in contact with the boiler and assisting in retaining at a very high temperature the released gases from the fuel, and also super-heating the air as it escapes into the fire-box from 100 the air-box, said air-heating box having an air inlet near the bottom, vertical flues in the air-heating box and an expansion chamber near the top of said box into which the flues discharge, the hot air being let into the 105 fire-box above the fuel, and means controlled by the door for admitting air into the air-heating box.

2. The combination of a boiler and its fire-box, a door therefor, an air-heating box in 110 the fire-box and below and adjacent to the door, said air-heating box having an air inlet near its bottom, vertical flues in the air-heating box and an expansion chamber within said box into which the flues deliver, 115 said expansion chamber having a cover of bricks inclined downwardly and inwardly within the furnace and below the door, said bricks having air outlets between them, through which outlets the heated air from 120 said expansion chamber escapes into the fire-box above the fuel, means for admitting air into the air-heating box, an arch in the fire-box arranged at an incline and extending substantially diagonally through the fire-box from a point substantially over the door 125 to the boiler, and dividing the fire-box into two chambers, said arch assisting in retaining at a high temperature the released gases from the fuel, and super-heating the air as 130

it escapes into the fire-box from the air-heating box.

3. The combination of a boiler and its fire-box, a plurality of slidable doors closing a charging opening in the fire-box, an air-box within the fire-box, and adjacent to, parallel with, and below the door, said air-box having inlets at its lower end, coacting dampers controlling said inlets, the air-box being provided with an expansion or superheating chamber having constricted outlets, means for protecting said outlets and preventing their becoming clogged, said doors being connected to open simultaneously, means carried by each door whereby the dampers are lifted synchronously, and means governing the lowering of said dampers.
4. The combination with a boiler and its fire-box, of an air-box located at the front lower corner of the fire-box and having a superheating chamber from which air is directed upwardly and rearwardly through inclined passages whose combined area is less than the area of inlet flues of the superheating chamber, slidable doors for closing
- a charging opening of the fire-box, dampers for controlling the admission of air into the air-box, said doors being connected by a link and lever, whereby they are operable in unison, and each being adapted to engage flexible members secured upon pivoted arms, said arms being linked to rods upon each of which said dampers are secured, whereby when said doors are opened the dampers are actuated, and means adapted to govern the descent of the dampers, said means including a cylinder, a piston having suitable valves reciprocal in said cylinder and a rod secured to said piston, and an arm carried by said piston-rod, the outer end of said arm being guided in a suitable slide and carrying said damper-rod.
5. The combination of a boiler and its fire-box, a plurality of slidable doors closing a charging opening in the fire-box, an air-box within the fire-box, and adjacent to, parallel with, and below the door, said air-box having inlets at its lower end, coacting dampers controlling said inlets, the air-box being provided with an expansion or superheating chamber having constricted outlets, means for protecting said outlets and preventing their becoming clogged, said doors being connected to open simultaneously, means carried by each door whereby the dampers are lifted synchronously, and means governing the lowering of said dampers.
20. The combination with a boiler and its fire-box, of an air-box located at the front lower corner of the fire-box and having a superheating chamber from which air is directed upwardly and rearwardly through inclined passages whose combined area is less than the area of inlet flues of the superheating chamber, slidable doors for closing
10. The combination of a boiler and its fire-box, a plurality of slidable doors closing a charging opening in the fire-box, an air-box within the fire-box, and adjacent to, parallel with, and below the door, said air-box having inlets at its lower end, coacting dampers controlling said inlets, the air-box being provided with an expansion or superheating chamber having constricted outlets, means for protecting said outlets and preventing their becoming clogged, said doors being connected to open simultaneously, means carried by each door whereby the dampers are lifted synchronously, and means governing the lowering of said dampers.
15. The combination with a boiler and its fire-box, of an air-box located at the front lower corner of the fire-box and having a superheating chamber from which air is directed upwardly and rearwardly through inclined passages whose combined area is less than the area of inlet flues of the superheating chamber, slidable doors for closing
25. The combination of a boiler and its fire-box, a plurality of slidable doors closing a charging opening in the fire-box, an air-box within the fire-box, and adjacent to, parallel with, and below the door, said air-box having inlets at its lower end, coacting dampers controlling said inlets, the air-box being provided with an expansion or superheating chamber having constricted outlets, means for protecting said outlets and preventing their becoming clogged, said doors being connected to open simultaneously, means carried by each door whereby the dampers are lifted synchronously, and means governing the lowering of said dampers.

In testimony whereof I have hereunto set my hand in presence of two subscribing witnesses.

EDWIN R. PHILLIPS.
